[57] **CLAIM**

The ornamental design for a anti-flex device for suitcases having deformable sidewalls, as shown and described.

DESCRIPTION

FIG. 1 is a side elevational view of an anti-flex device for suitcases having deformable sidewalls showing my new design, the front, rear and side views being mirror images thereof;

FIG. 2 is a top plan view thereof, the bottom view being a mirror image thereof;

FIG. 3 is an exploded parts view thereof; and,

FIG. 4 is a perspective view thereof in one possible environment.

The broken-line showing of environmental structure in FIG. 4 is for illustrative purposes only and forms no part of the claimed design.
